DESIGN FOR A DISPENSER FOR PAPER TAPE PRODUCT

Ferd H. Meyer, Oakland, Calif., assignor to The Adhesive Products Co., San Francisco, Calif., a corporation of California

Application November 24, 1937, Serial No. 73,154

Term of patent 7 years

To all whom it may concern:

Be it known that I, Ferd H. Meyer, a citizen of the United States and a resident of the city of Oakland, county of Alameda, State of California, have invented a new, original, and ornamental Design for a Dispenser for Paper Tape Product, of which the following is a specification, reference being had to the accompanying drawing forming part thereof.

Fig. 1 is a side elevation of a dispenser embodying my design;

Fig. 2 is a plan view of the same;

Fig. 3 is a rear view of the same looking from the left side of Fig. 1; and

Fig. 4 is a front view of the same looking from the right side of Fig. 1.

I claim:

The ornamental design for a dispenser for paper tape product, substantially as shown.

FERD H. MEYER.
